UNITED STATES PATENT OFFICE.

JAMES F. LOREMAN, OF CRISFIELD, MARYLAND, ASSIGNOR OF ONE-HALF
TO THOMAS H. BOCK, OF SAME PLACE.

DREDGE-CHOCK.

SPECIFICATION forming part of Letters Patent No. 269,803, dated December 26, 1882.

Application filed September 21, 1882. (No model.)

To all whom it may concern:

Be it known that I, JAMES F. LOREMAN, a citizen of the United States, residing at Crisfield, in the county of Somerset and State of Maryland, have invented certain new and useful Improvements in Dredge-Chocks, of which the following is a specification, reference being had therein to the accompanying drawings.

10 My invention relates to an improved anti-friction dredge-chock for use on oyster-dredging vessels, and will first be described, and then designated in the claims.

In the drawings hereto annexed, Figure 1 is 15 a front view of the chock. Fig. 2 is a front view of part, the upper end being in section. Fig. 3 is a side view transverse to that seen in Fig. 1. Fig. 4 is a side view of part, the upper end being in section. Fig. 5 is a cross-20 section of the chock. Fig. 6 shows the chock applied to the side of a vessel.

The letter A designates the body of the chock. The front side of the body has a half-rounded groove, b, extending lengthwise of its 25 central part. At each end of the groove is an abrupt shoulder, c. A rod, d, has its ends rigidly secured in these shoulders, and a number of balls, e, each having a diametrical hole, are mounted loosely on the rod. These balls are 30 slightly flattened at either side, where they are in contact with each other. The balls, by the yielding of the rod, may have bearing in the half-rounded groove, which furnishes a solid support, and therefore a very stiff rod, d, 35 for them to turn on, is unnecessary. The several balls turn independently of each other, and constitute a very superior anti-friction device, over which to draw the drag-rope I of a dredge. The uppermost ball has at its upper 40 side a broad flange, e', the upper side of which is a flat circular surface. A socket, f, is formed in the upper end of the body, and a friction-disk, g, is centrally pivoted in the socket. The position of this disk is such that at one point 45 its periphery bears against the flat circular surface of the uppermost ball, and, as the axis of the disk has position at a right angle to the rod on which the ball turns, it will be seen the

disk serves as a frictionless brace for the flanged ball. By this arrangement, whenever 50 the drag-rope works up against the projecting flange e', the latter prevents the rope from passing any higher up, while the disk braces and stays the uppermost ball and enables it to continue revolving, notwithstanding the 55 lateral or upward pressure occasioned by the rope bearing against the flange.

The particular shape of the ends of the chock is immaterial. Holes h are formed in the body, through which bolts or screws are passed, for 60 its attachment to the outer side of the gunwale L of a vessel.

My device has advantage over a mere grooved roller. The bracing-disk g may be usefully employed either with separate balls or a single long roller, and the half-rounded groove serves as a bearing for either separate balls or a single roller. As a bearing for the balls, this groove gives all the strength desired, without requiring much weight of metal in the rod or 70 balls. The device will save wear on the ropes and require less power at the windlass, by which the ropes are drawn.

Having described my invention, I claim and desire to secure by Letters Patent of the United States—

1. A dredge-chock the body of which has a straight half-rounded groove, b, a rod, d, extending along the groove, and balls e, mounted loosely on the rod, as set forth.

2. In a dredge-chock, the combination of the body A, provided at one end with a socket, f, and having a disk pivoted in the socket, a rod, d, secured on the body and extending at a right angle with respect to the axis of the disk, a 85 friction-roll mounted loosely on the rod, and provided with a flange, e', the side of which forms a flat circular surface adapted to bear against the periphery of the disk, as set forth.

In testimony whereof I affix my signature, in 90 presence of two witnesses, this 31st day of August, 1882.

JAMES F. LOREMAN.
